MOTION PICTURE CAMERA

Arthur H. Crapsey, Jr., Rochester, N.Y., assignor to
Eastman Kodak Company, Rochester, N.Y., a
corporation of New Jersey

Filed Apr. 5, 1962, Ser. No. 69,588

Term of patent 7 years

(Cl. D61—1)

FIG. 1.

FIG. 2.

FIG. 1 is a front perspective view of a motion picture camera showing my new design:

FIG. 2 is a rear perspective view thereof; and

FIG. 3 is a fragmentary detailed sectional view thereof taken on the line 3—3 of FIG. 2.

The characteristic feature of my design resides in the combination on the camera shown of a massive appearing front having a wide annular band extending outwardly of the rectangular camera body walls, and a front wall forward of the band and having a double stepped appearance forming three vertically spaced and substantially rectangular portions in which the lowermost portion has a symmetrically disposed control button, the intermediate portion is a mounting surface for an elongate cylindrical

lens barrel, and the uppermost portion presents an extended hood for optical elements; in conjunction with an elongate wedge shaped guard extending along a substantial length of one side wall of the camera body and having an arcuate cut out portion cooperating with a circular knob on a circular mounting, all as shown.

I claim:

The ornamental design for a motion picture camera, as shown.
